UNITED STATES PATENT OFFICE

147,418

DESIGN FOR A TIE RACK OR SIMILAR
ARTICLE

Ernest L. Persons, Meriden, Conn., assignor of
one-half to Ernest J. Martineau, Holyoke,
Mass.

Application March 22, 1946, Serial No. 127,800

Term of patent 3½ years

(Cl. D33—8)

To all whom it may concern:

Be it known that I, Ernest L. Persons, a citizen of the United States, residing at Meriden, in the county of New Haven and State of Connecticut, have invented a new, original, and ornamental Design for a Tie Rack or Similar Article, of which the following is a specification, reference being had to the accompanying drawings, forming part thereof.

The figure on the drawing is a front perspective view of a tie rack showing my new design.

The back of the tie rack shown in the figure is conventionally plain.

I claim:

The ornamental design for a tie rack or similar article, as shown and described.

ERNEST L. PERSONS.
